RAIL JOINT

Wilhelmina Sjöstrand, St. Paul, Minn.

Application October 24, 1946, Serial No. 705,450

4 Claims. (Cl. 238—169)

1

My invention relates to an improvement in rail joint wherein it is desired to provide a connecting means for connecting the abutting ends of two adjacent rail sections.

The object of the present invention resides in the provision of a connecting means which is inexpensive to manufacture and to install and which will hold the rails from creeping, sinking, or from lateral movement. The joint is so constructed, however, as to permit a predetermined amount of relative longitudinal movement between the abutting rail ends to permit the necessary expansion and contraction of the rails.

A feature of the present invention resides in the fact that my rail joint is composed of two connector elements, both of which are identical in construction. In view of the fact that both of the elements are identical in construction the rail joint can be economically made. Furthermore, in view of this construction it is not necessary to maintain in stock pairs of connecting elements, as would be necessary if the two elements were different in construction.

A feature of the present invention resides in the provision of a rail joint including two elements, each of which is provided with a longitudinal groove or channel therein of a size and shape to accommodate the base and web of a rail. In view of the fact that the rail is engaged within such a channel definitely prevents any lateral movement of the rail in the event a clamping bolt should become loosened.

A feature of the present invention lies in the provision of a connector including two main elements which are similar in construction and which are arranged in overlapping relationship. Each connector includes a channeled element designed to engage about opposite sides of a rail and an elongated arm which extends beyond the joint between the rails. The projecting end of each arm is connected to the base of the complementary rail joint section so as to provide a firm connector between rail ends.

An added feature of the present invention resides in the provision of a raised platform portion on each section of my rail joint on which the extremity of the rail may rest. The base of each rail is thus contacted by two spaced base engaging elements so as to equally support the end of each rail to prevent the same from sinking or

sagging. At the same time a portion of the base of the rail is spaced from the portions of the joint underlying the rail so as to permit the rail base to properly fit against the connecting members and to compensate for expansion and contraction of the connecting members.

These and other objects and novel features of my invention will be more clearly and fully set forth in the following specification and claims.

10 In the drawings forming a part of my specification:

Figure 1 is a top plan view of a rail joint, the major portion of the rails being broken away to show the construction of the connecting members.

15 Figure 2 is a side elevational view of the rail joint shown in Figure 1.

Figure 3 is a cross sectional view through the rail at one end of the rail joint.

20 The rail joint A is designed for use in holding lengths of rail B in abutting relationship. The rail joint A is comprised of two identical elements, each of which may be identified in general by the letter C. In view of the fact that the elements 25 C are identical, the parts thereof will be identified by the same numerals.

Each of the units C is provided with a rail engaging end 10 of a type best illustrated in Figure 3 of the drawings. The rail engaging end 10

30 includes a horizontally extending base portion 11 which is designed to underlie the base flange 12 of the rail B and to contact this rail base. Upwardly extending flanges 13 are provided at each side of the base 11 to extend over the side edges 35 of the base flange 12, these flanges 13 merging into inwardly converging flange portions 14 which overlie the upper surface of the base flange 12. The converging flange portions 14 terminate in parallel vertically extending flange portions 15 which extend on opposite sides of the web 16 of the rail B. The upper extremities 17 are curved to fit the curvature on the under-surface of the rail head 19. In other words, the flange portions 15 are shaped at their upper extremities to fit the shape or curvature of the junction between the rail web 16 and the rail head 19.

As will be noted from Figure 3 of the drawings, the rail engaging portion 10 is thus formed which extends on opposite sides of the rail and embraces a portion of the rail in such a way as

to hold the rail from lateral movement. Apertures 20 are provided in alignment through the opposed flange portions 15 and a similar aperture is provided in the rail B so as to accommodate a clamping bolt 21. The clamping bolt 21 extends through the opposed flanged portions 15 of the rail engaging end 10 and also through the web 16 of the rail B so as to clamp these elements together. A nut 22 is provided on the bolt 21 to permit the elements to be held in clamped relation.

A web 23 projects downwardly from the base portion 11 of the rail engaging element 10 and terminates in a transversely extending flange 24 having an upwardly projecting lip 25 on its extremity. The web 23 forms the anchor end of the arm 26 which projects from the rail engaging end 10 past the butt joint between the rail ends B. The web 23 is provided with an elongated aperture 27 therethrough while the free end 29 of each arm 26 is provided with a cooperable aperture 30 therethrough. The apertures 27 and 30 are designed to accommodate clamping bolts 31 provided with suitable clamping nuts 32 by means of which the free end of one arm 26 may be attached to the web end 23 of the other arm.

Each of the arms 26 is provided with an upwardly projecting portion 33 which extends upwardly into engagement with the base 12 of the rail B. In other words, the projections 33 form a support for the rail sections B near the extremities thereof. The upwardly extending projection on one of the connecting members C engages the rail on one side of the joint and the projection 33 of the other connecting member C engages the other rail B on the opposite side of the butt joint. The base of each rail section B is thus engaged at two spaced points and the connecting members are spaced from the rail base intermediate these points.

As best illustrated in Figures 2 and 3 of the drawings the arms 26 are provided with a downwardly curved lower edge 34 which increases the depth of each arm at a point midway between the ends thereof. Also as illustrated in Figure 3 of the drawings each arm 26 is provided with a bead or flange 35 along this lowered edge to increase the thickness of the arms at this point and to accordingly increase the strength thereof. Transversely extending reinforcing ribs 36 are provided beneath each web 23 so as to strengthen the flange 24 beneath the free end of the cooperable arm 26.

As best noted in Figures 2 and 3 of the drawings the flange 24 of each member C is provided with an inclined upper surface 37. This inclined upper surface 37 is lower at one end than at the other so as to provide an inclined longitudinal surface. A wedge 39 is positioned between each inclined surface 37 and the lower edge 40 of the free end of the cooperable arm 26 so as to hold the free end of each arm in proper relation to the rail engaging end of the cooperable connecting member. These wedges 39 at each end of the rail joint A provide a means of insuring engagement of each of the connecting members C with its respective rail.

In attaching the connecting elements C to the rails B, a rail engaging end 10 is slidably engaged on a rail and on each side of the butt joint and

the connecting elements are moved until the apertures therethrough are in proper alignment. The bolts 21 are put into place to connect each rail embracing end 10 to its respective rail and the arms 26 are placed at the proper elevation by means of the wedges 39. The bolts 31 are then inserted through the aligned apertures in the web ends 23 and the free ends 29 of the two arms to hold the rail ends in proper relationship. The connecting members C hold the rails from movement longitudinally by engagement between adjacent ties and hold the individual rails from vertical or lateral movement while engaged.

In accordance with the patent statutes, I have described the principles of construction and operation of my rail joint and while I have endeavored to set forth the best embodiment thereof, I desire to have it understood that this is only illustrative thereof and that obvious changes may be made within the scope of the following claims without departing from the spirit of my invention.

I claim:

1. A rail joint including a pair of identical members, each having a rail embracing end attached to and spaced from a rail end including a base portion designed to extend beneath the rail and a pair of integral flanges designed to extend over the base of the rail on each side thereof, and against the web of the rail, clamping means extending through the opposed flanges and through the portion of the rail web therebetween to clamp said flanges against the rail, one such rail embracing end being positioned near the end of each of the rails being joined, an arm integral with the bottom portion of each of the rail embracing ends to extend longitudinally of the rail and beneath the level thereof and across the rail end, the free end of one arm being arranged adjacent the end of the other arm attached to the rail embracing end, and clamping means extending through the ends of the arms for holding the arms in side by side relation.

2. The structure defined in claim 1 and including a platform portion on each of said arms at a point spaced from the integral rail engaging end engaging one rail designed to contact the undersurface of the other rail.

3. The structure defined in claim 1 and including an integral flange on the end of the arm attached to the rail embracing end designed to extend beneath the free end of the other arm to support said arm.

4. The structure defined in claim 1 and including a tapered flange on the end of each arm attached to the rail embracing end designed to extend beneath the free end of the other arm, and wedge means engaged between the free end of the other arm and said flange.

WILHELMINA SJOSTRAND.
